Atty.

UNITED STATES PATENT OFFICE.

ADOLPH C. RECKER, OF WATERTOWN, CONNECTICUT, ASSIGNEE TO CHASE COMPANIES, INC., OF WATERBURY, CONNECTICUT, A CORPORATION.

ADAPTER FOR ELECTRIC-LAMP SOCKETS.

Application filed April 5, 1924. Serial No. 704,331.

Fig. 1 is a view in side elevation of my improved adapter, as constructed for use with "miniature" bulbs, shown on the double scale.

5 Fig. 2 is a plan view thereof.

Fig. 3 is a view thereof in central section, showing it as applied to a standard socket of the "Edison" type, shown in broken lines.

10 Fig. 4 is a view in central section of a modified form of my improved adapter, shown as designed for use with "candelabra" bulbs.

15 My invention relates to an improved adapter for electric lamp-sockets, the object being to provide, at a low cost for manufacture, simple, convenient and effective means, whereby a standard lamp-socket of the "Edison" type may be adapted or converted for use with bulbs having small stems, 20 such as the so-called "candelabra" and "miniature" bulbs.

With these ends in view, my invention consists in an adapter for electric lamp-sockets having certain details of construction 25 and combinations of parts as will be herein-after described and particularly pointed out in the claim.

30 In carrying out my invention, as herein shown, I employ a screw-shell 5 having standard screw-threads to fit a lamp-socket of the "Edison" type and having its upper edge turned inwardly to form a reflector 6, the edge of which has clamped upon it the outer end of a concentric sheet-metal shell 35 7 threaded to correspond to the threads of the stem of a "miniature" bulb, and therefore considerably smaller in diameter than the screw-shell 5 within which the smaller shell 7 may be said to be suspended. At its

inner end, the smaller shell 7 mounts an insulating disk 8 carrying a centrally-arranged contact-stem 9 adapted in length to engage with the center-contact 10 of the socket 11 of a standard socket of the "Edison" type, the said contact and socket being 45 shown by broken lines.

When the "miniature" bulb has its stem screwed into the inner shell 7, it is in electrical connection with the outer shell 5, while the bulb's center-contact is in electrical connection with the center-contact of the socket 11 through the stud 9.

50 In the modification shown by Fig. 4, the screw-shell 5 is formed with a flange 12 turned inwardly at a right angle and having superimposed upon it a flanged disk 13 of insulating material held in place by crimping upon it at 14 the outer end of a concentrically-arranged inner shell 15, adapted in size and threading to correspond to the size 55 and threading of a so-called "candelabra" bulb. In this case, the adapter is screwed into and out of the standard socket by grasping the flanged edge of the insulating disk 13, whereby the user is protected against 60 shock.

65 I claim:

In an adapter for electrical lamp-sockets, the combination with a threaded shell, provided at one end with a reflector, of a smaller inner shell supported by the said reflector concentrically within the outer shell, and a contact-stem mounted in the opposite end of the inner shell and insulated therefrom.

70 75 In testimony whereof, I have signed this specification.

ADOLPH C. RECKER.
